UNITED STATES PATENT OFFICE.

DAVID C. KLAUSMEYER, OF CINCINNATI, OHIO, ASSIGNOR TO THE CINCINNATI BICK-FORD TOOL COMPANY, OF CINCINNATI, OHIO, A CORPORATION OF OHIO.

RADIAL DRILL ARM.

Application filed April 4, 1923. Serial No. 629,853.

To all whom it may concern:

Be it known that I, DAVID C. KLAUSMEYER, a citizen of the United States, and residing at Cincinnati, in the county of 5 Hamilton and State of Ohio, have invented a new and Improved Radial Drill Arm, of which the following specification is a full disclosure.

This invention relates to radial drills, and 10 has for its primary object an improved structure of the radial arms for such drills, and also improvements in the structure of the heads mounted thereon.

In radial drills for heavy service, such 15 radial-arms are massive members, (some times reaching a length of from six to ten feet) and in order to provide a structure as light as possible consistent with the requisite strength, it is customary to form the 20 radial-arm as a hollow casting. In forming these castings a mold is employed having cores supported laterally from the walls of the mold at a multiplicity of points, forming holes in the sides of the arm through which 25 the cores are removed, these holes remaining in the finished arm as so many regions of weakness, and detracting from the neat appearance of the arm.

The objective of this invention is to produce 30 a radial-arm-casting free from the weakening core-holes, and constituting when finished an arm-structure of greatly increased stability, capable of resisting the torsional strains to which these arms are 35 subjected in use, the finished arm being also much neater in appearance by reason of its uninterrupted contour.

For effecting the above improvement, a mold for casting such radial arms is provided 40 with a core-portion, or preferably a plurality of core-portions, extending substantially parallel with the longitudinal axis of the arm, to produce a casting having a cross-section a plurality of parallel chambers, with intervening longitudinal partitions, for the sake of strength.

Each such lengthwise core-portion is supported by the walls of the mold at the region 45 which forms the outer end of the radial-arm, so that in the casting there will be formed holes of a size adequate for the removal therethrough of the core-portions, but negligible in their effect upon the strength and appearance of the finished arm.

The above-described longitudinal core-portion or portions are preferably formed in connection with a transverse core-member at the other end of the mold for the radial-arm, at the region of the mold where is to be formed the so-called "barrel" of the arm, 55 i. e. the sleeve-like part that is fitted eventually upon the upright column of the machine, this connection between the lengthwise core-portions and the large barrel-core yielding an extremely solid and advantageous support for the lengthwise core-portions at their inner ends, and not resulting in the formation of any exterior orifice in the casting, as this connection between the core-portions occurs within the region at 60 which the radial-arm springs from its barrel, the longitudinal chambers merging respectively into the barrel-bore.

Another important object of this invention is to improve the mode of mounting, 75 upon such a radial arm, the sliding head which carries the drill, to provide for improved alignment of the head with the arm, greater ease of movement of the head along the arm, and increased stability of 80 the head upon the arm, these objects being accomplished by forming the arm and head with a main bearing of improved structure.

Ordinarily, the bearings between the radial-arm and its sliding head comprise the main-bearing to the improvement of which the present invention is directed, and an auxiliary-bearing which may, and preferably will, be of any well-known or suitable 85 structure.

As heretofore constructed, the main-bearing between the radial-arm and sliding-head is formed with co-operating front vertical bearing-surfaces on the arm and head respectively, also tapered lower bearing-surfaces on the arm and head respectively, and upper, horizontal surfaces on the arm and head respectively, with a narrow guiding arrangement including a taper-gib, 90 interposed between the aforesaid horizontal surfaces, and which performs the double duty of sustaining the weight of the head, and of cramping the vertical bearing-surface of the head against that of the arm, through 95 the wedging action of the co-operating tapered bearing-surfaces.

The accurate formation of these tapered surfaces has constituted an indispensable

and costly operation having unsatisfactory results, as such tapered surfaces are difficult to form and maintain in closely fitting relation, while the double duty imposed on the primary guide is unduly severe, and the total area of the main-bearing-surfaces is inadequate, so that the sliding-head lacks stability and perfect alignment upon the radial-arm, and is not movable easily thereon.

To obviate these disadvantages, in carrying this invention into effect, and in contradistinction to the above recited mode of construction, the main-bearing is formed with a rectangular guiding-member on the radial arm, instead of the V-shaped lock-guiding member heretofore used, the main-bearings comprising a plurality of horizontal bearing-regions, which are designated herein as the "upper main bearing" and the "lower main bearing" respectively; also a plurality of vertical bearings, which are designated as the "front main bearing" and the "rear main bearing" respectively; and to co-operate therewith a plurality of adjustable taper-gibs or narrow guide members are provided, with means to secure them in adjusted position, and which are designated as the "primary-guide" and the "secondary guide," respectively, using these expressions for the sake of brevity and without technical limitation.

The bearing-surfaces on the sliding-head engage the rectangular-guiding-member of the arm on portions of four sides, so that the aggregate area of the main-bearings is greater than that of the usual main-bearings embodying a tapered structure, and yields greater stability to the head, while a more perfect alignment of the head on the arm is secured by the plural guide-members, the primary guide being interposed between the head and arm at the region of the upper horizontal main bearing-portion, serving to sustain the weight of the head, and also to maintain both the upper and lower main horizontal bearing-ports in snugly-fitting relation, while the secondary guide is interposed between the head and the arm between the front and the rear main vertical bearing-ports, and serves to maintain both the front and rear main vertical bearing-ports in snugly-fitting relation, relieving the primary-guide of the duty of any vertical alignment, so that the sliding motion of the head on the arm is accomplished more easily than in existing structures, the improved arm and head structure thus effecting the important purposes which this invention has been devised to accomplish, as above set forth.

Other objects and advantages will be in part indicated in the following description and in part rendered apparent therefrom in connection with the annexed drawings,

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:—

Fig. 1 shows in front elevation a radial-arm, with its sliding-head in place thereon. Fig. 2 is a vertical section on the line 2—2 of Fig. 1, and Fig. 2^a is an enlarged fragmentary detail view thereof. Fig. 3 is a plan view of the radial arm, isolated. Fig. 4 is a longitudinal, vertical section on the line 4—4 of Fig. 3. Fig. 5 is a transverse, vertical section on the line 5—5 of Fig. 4.

Referring to the drawings, it will be seen that the radial-arm comprises a barrel portion 1 to be fitted upon the usual upright column of a radial drill, and an arm-portion 2 which extends from the barrel and serves as the supporting member for the drill-head 3 mounted slidably thereon, the barrel portion being shown as of well-known construction in its general arrangements, having a bore 4 to receive the column, and being split at 5, with lugs 6 to receive suitable means for securing the radial-arm in adjusted position upon its supporting column.

The arm-portion 2 is shown as a hollow structure, divided longitudinally by lengthwise extending partitions 7 into a plurality of longitudinal chambers 8, 9, 10 and 11 open respectively at their outer ends, and of which several are shown as communicating at their inner ends with bore 4 of the barrel 1, the exterior lateral walls 12 of the arm being substantially uninterrupted in contour and thus free from the core-holes which weaken and disfigure radial-arms as constructed heretofore.

The above improved structure may be produced by any suitable method, and as an advantageous method of formation use may be made of a mold having a plurality of longitudinal core-members corresponding to the longitudinal chambers 8, 9, 10 and 11, these longitudinal core-members being supported at their outer ends by the walls of the mold at regions adjacent to the outer openings 13, 14, 15 and 16 of the chambers, through which the material of the cores may be removed. At their inner ends the cores may be supported by any suitable means, and in the instance of the cores for the chambers 9, 10 and 11 it will be found advantageous to support the cores from the transverse core-member used to form the barrel 1, which is essentially of substantial thickness and will afford ample support to the longitudinal core-members.

By this mode of formation a hollow arm

is produced of light structure by reason of its longitudinal chambers, but so strengthened by its inner partitions, and by having exterior walls of uninterrupted contour, 5 that it is much better fitted, than are existing radial-arms, to sustain the torsional strains to which such arms are subjected in use, and it presents a much neater appearance with its uniformly continuous lateral 10 walls than do the existing arms with their unsightly core-holes.

Referring to Figs. 1, 2, 2^a, 3 and 5 of the drawings, it will be seen that the supporting member 2 of the radial arm is provided with a plurality of longitudinal bearings 17 and 18, the bearing 17 constituting the main longitudinal bearing of the arm, while the bearing 18 is an auxiliary longitudinal bearing and may be 20 of any suitable character, being shown as of a well-known type that does not require special description, it being sufficient to note that it co-operates with a bearing surface 19 upon the drill-head 3, as shown in Fig. 2, the head being provided with a retaining member 20, secured thereto by suitable means, not shown.

In accordance with an important object of this invention, which is to provide better 30 alignment of the head 3 upon the arm 2, increased stability thereof, and greater ease of sliding movement, provision is made by this invention for a main bearing of greater area than is found in the main bearings of 35 existing radial arms which employ a tapered lower bearing surface as part of the main bearings.

In the improved structure illustrated, the main bearing is formed with a plurality of horizontal bearing surfaces, of which the upper horizontal main bearing surface is designated by the reference character 21 and the lower bearing surface by the numeral 22, and also has a plurality of vertical bearing surfaces, of which the front surface is indicated at 27 and the rear surface at 34, these surfaces together forming a series of rectangular lock-guiding bearings. The head 3 is shown as provided with main 45 bearing surfaces corresponding respectively to the above main bearing surfaces, and comprises an upper bearing surface 25 corresponding to the arm surface 21, a lower horizontal bearing surface 26 corresponding to the arm bearing surface 22, a vertical bearing surface 27 corresponding to the arm bearing surface 24 and a bearing portion 28 corresponding to the rear vertical arm bearing surface 34, the above mentioned 50 main bearing portions upon the head engaging the rectangular main bearing portions of the arm on parts of four of its sides, so that the aggregate area of these bearings is considerably greater than that of the 55 area of a main bearing employing lower ta-

pered main bearing surfaces as used in existing radial arms of this type. There will preferably be a slight clearance between the arm and head along the vertical region 23.

In accordance with another object of this invention, there is provided a plurality of guides, comprising a primary guide 29 and a secondary guide 30, the primary guide 29 being interposed between the head 3 and arm 2 at the region of the upper horizontal bearing, where it will be seen in Fig. 2 between the surfaces 21 and 25, serving to sustain the weight of the head and also to maintain in snugly fitting relation the surfaces 22 and 26 composing both the upper and lower main horizontal bearings.

The secondary-guide 30 is shown as interposed between the rear vertical bearing surfaces 24 and 28 and serves to maintain in snugly fitting relation both of the vertical main bearings, holding the surface 27 of the head against the surface 24 of the gib, and the surface 28 of the head against the surface 34 of the arm. The above guide 30 members 29 and 30 may be of any suitable material and construction and as one convenient form of structure they are shown as respectively comprising narrow taper gibs provided with adjusting screws 31 and 32 respectively.

It will, therefore, be seen that this invention provides a radial arm for radial drills, comprising an extended supporting member and a head mounted slidingly thereon, said supporting member being provided with main longitudinal bearings comprising upper and lower horizontal bearing portions and front and rear vertical bearing portions, and said sliding head having main horizontal and vertical bearing portions corresponding respectively with said main bearing portions on said supporting member, and a plurality of narrow guides comprising a primary guide interposed between said supporting member and head at the region of said upper horizontal main bearing portions, to maintain said upper and lower horizontal main bearing surfaces on said supporting member and head in snugly fitting relation, and a secondary-guide interposed between said supporting-member and head between the front and rear vertical main-bearing-portions, to maintain said front and rear vertical main-bearing-surfaces in snugly fitting relation, said primary and secondary guides including respectively an adjustable taper-gib and means to secure the same in adjusted position, and said main bearing-surfaces on said supporting-member constituting a structure having rectangular bearing-surfaces, and engaged on portions of four sides by said bearing-surfaces on said head.

The rectangular lock-guiding-bearing

thus formed has considerably greater aggregate area than the conventional bearings with a tapered lower surface, and accordingly the sliding-head is maintained in more accurate alignment with the arm, moves more easily thereon, and has greatly increased stability in its relation to the arm. Without further analysis, the foregoing will so fully reveal the gist of this invention that others can, by applying current knowledge, readily adapt it for various utilizations by retaining one or more of the essential characteristics of either the generic or specific aspects of this invention, and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of the United States:

1. A radial-arm for radial drills, said arm comprising a unitary structure providing a bearing end and a hollow cellular arm-portion extending therefrom; said bearing end of the arm being adapted to engage a suitable support for the arm, said cellular arm-portion having interior partitions in the nature of reinforcements and subdividing the interior into several chambers, the exterior lateral walls of said cellular arm-portion being free from core-holes and thereby continuous and uninterrupted.

2. A radial-arm for radial-drills, said arm comprising a structure having a transverse barrel-portion and an arm-portion with a plurality of longitudinal chambers separated by longitudinal partitions.

3. A radial-arm for radial-drills, said arm comprising a unitary structure having a transverse barrel-portion and an arm-portion with a plurality of longitudinal chambers separated by longitudinal partitions, the exterior lateral walls of said arm-portion being substantially uninterrupted.

4. A radial-arm for radial-drills, said arm comprising a unitary structure having a transverse barrel-portion with a barrel-bore and an arm-portion with a plurality of longitudinal chambers opening into said barrel-bore and separated by longitudinal partitions.

5. A radial-arm for radial-drills, said arm comprising an extended supporting-member and a head mounted slidably thereon, said supporting member being provided auxiliary and with main longitudinal bearings said main bearing comprising a plurality of horizontal bearing-ports and a plurality of spaced vertical bearing-ports, and said sliding head having horizontal and vertical bearing-ports corresponding respectively with said main bearing-ports on said sup-

porting-member, the vertical bearing portion of the head extending between the vertical bearings of the arm.

6. A radial-arm for radial-drills, said arm comprising an extended supporting-member and a head mounted slidably thereon, said supporting member being provided with auxiliary and main longitudinal bearings said main bearing comprising a plurality of horizontal bearing-ports and a plurality of opposed and facing vertical bearing-ports, and said sliding head having horizontal and vertical bearing-ports corresponding respectively with said main bearing-ports on said supporting-member, said main bearing-surfaces on said supporting-member constituting bearings substantially rectangular in cross-section, and engaged on portions of four sides by said bearing-surfaces on said head, the vertical bearing portions of the head extending between the vertical bearings of the arm.

7. A radial-arm for radial-drills, said arm comprising an extended supporting-member and a head mounted slidably thereon, said supporting member being provided with auxiliary and main longitudinal bearings said main bearing comprising upper and lower horizontal bearing-ports, and front and rear opposed vertical bearing-ports arranged with a space therebetween, and said sliding head having horizontal and vertical bearing-ports corresponding respectively with said main bearing-ports on said supporting-member, the vertical bearing portion of the head engaging the opposed bearing portions of the arm.

8. A radial-arm for radial-drills, said arm comprising an extended supporting-member and a head mounted slidably thereon, said supporting member being provided with auxiliary and main longitudinal bearings said main bearing comprising upper and lower external horizontal bearing-ports, and front and rear internal vertical bearing-ports, and said sliding head having horizontal and vertical bearing-ports corresponding respectively with said main bearing-ports on said supporting member, said main bearing-surfaces on said supporting-member being engaged on portions of four sides by said bearing-surfaces on said head, two of the bearing surfaces of said head projecting between and being in contact with the internal bearing surfaces of said arm.

9. A radial-arm for radial drills, said arm comprising an extended supporting-member and a head mounted slidably thereon, said supporting member being provided with auxiliary and main longitudinal bearings, said main bearing comprising a plurality of horizontal bearing portions contacting with bearing portions provided by said head to prevent vertical movement between the two;

and a plurality of horizontally spaced vertical walls provided by the lower portion of said main bearing and constituting a guideway, said head being provided with a guide 5 projecting into said guideway and engaging said vertical walls to prevent relative horizontal movement between said head and said arm.

In witness whereof, I hereunto subscribe my name, as attested by the two subscribing **10** witnesses.

DAVID C. KLAUSMEYER.

HILDA HERBERS.

Certificate of Correction.

It is hereby certified that in Letters Patent No. 1,523,596, granted January 20, 1925, upon the application of David C. Klausmeyer, of Cincinnati, Ohio, for an improvement in "Radial Drill Arms," errors appear in the printed specification requiring correction as follows: Page 1, line 43, for the article "a", second occurrence, read *in*; page 3, line 6, for the misspelled word "torsinal" read *torsional*; page 4, line 58, claim 5, after the word "provided" insert the word *with*, and line 59, strike out the word "with"; and that the said Letters Patent should be read with these corrections therein that the same may conform to the record of the case in the Patent Office.

Signed and sealed this 17th day of February, A. D. 1925.

[SEAL.]

KARL FENNING,
Acting Commissioner of Patents.
